UNITED STATES PATENT OFFICE.

ERNEST L. PRATT, OF LITCHFIELD, CONNECTICUT.

BLIND-FASTENER.

971,789.

Specification of Letters Patent.

Patented Oct. 4, 1910.

Application filed February 19, 1910. Serial No. 544,891.

To all whom it may concern:

Be it known that I, ERNEST L. PRATT, a citizen of the United States, residing at Litchfield, in the county of Litchfield and 5 State of Connecticut, have invented a new and useful Blind-Fastener, of which the following is a specification.

It is the object of this invention to provide a device adapted to be secured to the meeting 10 edges of a pair of blinds, not only to hold the blinds together, but, as well, to retain the slats of the blinds either in a closed or in a partially open position.

Another object of the invention is to provide 15 a pair of resilient arms, adapted at their adjacent ends, to interlock in a novel manner; and to provide the said arms, at their remote ends, with novel means for engaging the rods whereby the slats of the 20 blinds are connected.

Another object of the invention is to provide 25 a member adapted to be mounted upon the rod whereby the blind slats are connected, the said member being arranged to interlock with one of the hereinbefore mentioned resilient arms.

With the above and other objects in view, the invention consists in the novel construction and arrangement of parts hereinafter 30 described, delineated in the drawings, and claimed, it being understood that changes, properly falling within the scope of what is claimed, may be made, without departing from the spirit of the invention.

Similar numerals of reference are employed 35 to denote the corresponding parts throughout the several figures of the drawings.

In the accompanying drawings, Figure 1 40 is a front elevation showing a pair of blinds equipped with the locking device of my invention, the parts thereof being disposed in their locked positions; Fig. 2 is a fragmental front elevation showing the component portions 45 of the locking device spaced apart, and in unlocked position; Fig. 3 is a section showing one end of one of the resilient arms and the interlocking elements thereon; Fig. 4 is a transverse section of the device taken 50 adjacent the meeting edges of the blinds; Fig. 5 is a perspective showing of one of the plates wherewith the resilient arms are connected; Fig. 6 is a section of one of the base plates and of the parts which interlock there-

with; and Fig. 7 is a detailed perspective of 55 a modified form of the invention.

In the drawings, the stiles upon the meeting edges of a pair of blinds, are shown, and denoted by the numeral 1. The slats of the blinds are denoted by the numeral 2; and 60 the rods whereby the slats 2 are connected, by the numeral 3.

In carrying out my invention, I secure to the stiles 1, a pair of plates 4. These plates 4, upon their meeting edges, are provided 65 with arms 5, outstanding substantially at right angles to the said plates. Upon these arms 5 are mounted transverse heads 6, which, as shown most clearly in Fig. 6, stand upon their remote faces, beyond the 70 arms 5, the plates 4, the arms 5 and the heads 6 being preferably formed integrally.

The invention further includes a pair of resilient arms 7. To the outer faces of these arms 7 are secured plates 8. There are 75 elongated openings 9 extended through the arms 7 and through the plates 8, these openings 9 being adapted to receive retaining elements 10, extended into the plates 4, and constituting pivot elements, upon which the 80 arms 7 may move, both pivotally and slidably. In the adjacent edges of the plates 8 and the arms 7, there are notches 11. These notches are adapted to clear the portions 5 of the plates 4, to allow the adjacent edges 85 of the arms 7 to be brought together when the arms are tilted. These notches 11 moreover enable the arms 7 to be slid longitudinally upon each other, after their adjacent edges have been brought together by moving 90 the arms 7 pivotally upon the retaining elements 10. As shown at 12, the plates 8 overhang the arms 7 at one end of the plates, while at the other end of the plates, the arms 7 stand beyond the plates 8, as shown at 95 14. The overhanging portion 12 of the plate 8 is terminally provided with an outstanding finger 15 which is spaced apart from the arm 7. At the other end of the plate 8 there is an arm 16 which is rectangularly disposed 100 with respect to the resilient arm 7 upon which the plate 8 is mounted. The arm 16 has a rectangularly disposed extension 17, extended parallel to the arm 7, and the extremity of the arm 16 is rounded and bent 105 over as shown at 18. Beneath this rounded portion 18, an auxiliary plate 19 is secured to the plate 8. The extremities of the re-

silient arms 7 are curved to form finger holds 20 and adjacent these finger holds there are laterally extended shoulders 21, preferably formed integrally with the arms 7.

5 Curvilinear plates 22 are secured to the slat rods 3, these plates 22 being notched upon their edges to form tongues 24, outstanding from the plates 22.

In Fig. 7 of the drawings a modified form 10 of the invention is shown. In this form of the invention, the arm 25 is provided with an outstanding U-shaped element 26 adapted to fit over the slat rod 3, one end of the arm 25 being pivotally secured to a plate 27, which, in its turn is adapted to be secured to the upright stiles 1 of the blinds, and to be disposed substantially as are the plates 4 in Fig. 1 of the drawings.

Let it be supposed that the component 20 elements of the invention are disposed as shown in Fig. 2. Then the operation of the device is as follows:—When the remote ends of the arms 7 are seized and swung in opposite directions the arms will rotate upon 25 the retaining elements 10. As the adjacent edges of the arms move toward each other, the outstanding portions 14 of the arms 7 will move beneath the overhanging portions 12 of the plates 8, the rounded ends 18 of 30 the arms 16 enabling the said arms 16 to ride up smoothly over the arms 7, transversely of the same. When the meeting edges of the arms 7 are thus brought into abutment, the said arms may be slid in 35 opposite directions, the elongated openings 9 permitting this movement. When the arms are thus slid in opposite directions, the members 7 at the ends of the notches 11, engage beneath the heads 6 of plates 4, thus 40 causing the slidably mounted portions of the device to interlock with the heads 6. The fingers 15 will likewise slide across the arms 16 and bear against the edges of the auxiliary plates 19. The extensions 17 will, at 45 the same time lock into the angles denoted by the numerals 28 in Fig. 2. It will thus be seen that when the arms 7 are moved pivotally and slid longitudinally, there will be a plurality of interlocking elements at 50 the adjacent ends of the said arms, holding the said adjacent ends of the arms together securely.

The operation last above described relates 55 merely to the function exercised by the invention as a means for holding two blinds together. The device, however, serves not merely as a blind lock, but, as well, as a means for holding the movable slats of the blinds, either in a tightly closed or in a 60 partially open position. Passing now to the operation of the device, considered as a means for limiting the movement of the slats of the blinds, it will be seen that when the arms 7 are drawn in opposite directions, 65 as hereinbefore described, the remote ends

of the said arms may, by means of the finger holds 20, be lifted, so that the shoulders 21 will clear the tongues 24 upon the plates 22, the resiliency of the arms 7 causing the said shoulders, when the arms are 70 released to interlock with the tongues 24, the body of the arms 7 registering between the said tongues. These resilient arms 7 bearing against the plates 22 will obviously hold the slats 2 in a closed position, the 75 tongues 24 preventing the slat rod 3 from being moved longitudinally. However, by lifting the ends of the arms 7 slightly, the slat rods 3 may be moved longitudinally, so that the arms 7 may be made to register between the successive sets of the tongues 24, thus permitting the slats 2 to stand entirely open, or partially open, as well as in an entirely closed position. It has been pointed 80 out hereinbefore that the adjacent ends of the arms 7 are adapted to interlock against pivotal movement, and by the reason of this fact, it will be impossible for the slats 2 to be tilted or rattled by the wind; the slats 2 85 obviously being controlled by the rods 3, and the rods 3 being firmly engaged by the remote ends of the arms 7, which said arms, at their adjacent ends are, as hereinbefore pointed out, securely interlocked against 90 pivotal movement.

To unlock the blinds, and likewise to set the slats 2 free, the remote ends of the arms 7 are lifted out from between the tongues 24. The arms 7 are then slid longitudinally toward each other, to break the engagement 100 between the interlocking elements hereinbefore described, whereupon the arms 7 may be swung into a position in alinement with the stiles 1, whereupon the blinds may be opened.

105 It should be noted that each of the arms 7 is operative, when the blind is swung open, to hold the slats 2 in the manner hereinbefore described, the arm 7 in such case merely exercising its resilient function against the 110 slat rod 3.

The device shown in Fig. 7 is adapted to be used when it is desired merely to hold the slats 2, without locking the blinds together. The device shown in Fig. 7 is merely a 115 simplified form of the device shown in the preceding figures.

Having thus described the invention, what is claimed is:—

1. A device for securing blind slats, consisting of a resilient arm; means for securing the arm to a blind for both pivotal and longitudinal sliding movement, the arm being pivotally movable to overhang the slats of the blind; and means engageable by the 120 arm when the same is slid longitudinally, to lock the arm against pivotal movement.

2. A device of the class described comprising arms arranged to be pivotally mounted upon a pair of blinds adjacent the 125

meeting edges thereof, and having elements at their adjacent ends to interlock with each other, the arms at their remote ends being operable to hold the slats of the blinds 5 against movement.

3. A device of the class described comprising resilient arms arranged to be pivotally mounted upon a pair of blinds adjacent the meeting edges thereof, and having elements at their adjacent ends to interlock with each other, the arms being arranged at their remote ends to bear yieldingly upon the slat rods of the blinds. 10

4. A device of the class described comprising resilient arms arranged to be secured to a pair of blinds adjacent the meeting edges thereof, and having interlocking elements at their adjacent ends, the arms being arranged at their remote ends to hold 20 the slats of the blinds against movement; the arms being pivotally movable to dispose their remote ends in slat holding position, and being slidably movable to bring the interlocking elements into engagement. 25

5. A device of the class described consisting of members arranged to be secured to the slat rods of a pair of blinds; arms arranged to be pivotally mounted upon the blinds adjacent the meeting edges thereof and having elements at their adjacent ends to interlock with each other, the arms, at their remote 30 ends, and the rod carried members being arranged to interlock at predetermined steps, when the slat rods are shifted longitudinally. 35

6. A device of the class described comprising members arranged to be secured to the slat rods of a pair of blinds; resilient

arms arranged to be secured to the blinds adjacent the meeting edges thereof and having interlocking elements at their adjacent ends; the arms being arranged at their remote ends to interlock at predetermined steps with the rod carried members when the slat rods are shifted longitudinally; the 40 arms being pivotally movable to bring the interlocking elements at their adjacent ends together and to dispose their remote ends in position to interlock with the rod carried members; the arms being slidable to engage 45 the rod carried members and to cause the interlocking elements at their adjacent ends to engage with each other. 50

7. A device of the class described comprising base plates arranged to be secured to a pair of blinds adjacent to the meeting edges thereof; resilient arms secured to the base plates and arranged at their remote ends to hold the slats of the blinds in closed position, the adjacent ends of the arms being 55 arranged to interlock with the plates; there being mutually interlocking elements upon the adjacent ends of the arms; the arms being pivotally movable into their slat holding positions, and being slidably movable to 60 cause the mutually interlocking elements to engage with each other, and to cause the adjacent ends of the arms to interlock with the plates. 65

In testimony that I claim the foregoing 70 as my own, I have hereto affixed my signature in the presence of two witnesses.

ERNEST L. PRATT.
